CLAIM

The ornamental design for a blank for forming a container, as shown and described.

DESCRIPTION

FIG. 1 is a front view of a blank for forming a container in accordance with the present invention;

FIG. 2 is a top view thereof;

FIG. 3 is bottom view thereof;

FIG. 4 is left side view thereof; and,

FIG. 5 is a right side view thereof.

The broken lines in the drawings depict cut lines where the material of the blank for forming a container has been cut.
